UNITED STATES PATENT OFFICE

HERBERT R. WILSON, OF TOLEDO, OHIO

SYSTEM OF COLUMN HEADINGS

Application filed October 20, 1930. Serial No. 489,761.

This invention relates to a system of column headings intended primarily for use in connection with stock quotation boards. In order that the quotations of a large number of different stocks may be posted in as small space as practicable, with a separate column for each individual stock, the columns are necessarily narrow, so that there is barely room at the top of each one to receive the 5 ticker symbol of the stock quoted therein. Inasmuch as many people are unfamiliar with these ticker symbols, it is a common practice to print the full name of the stock, or a readily recognized abbreviation of the 10 same, in a vertical or diagonal line at the head of the column. These names however, because of their position, are rather difficult to read.

With the above conditions in mind, it is 20 an object of the present invention to provide a system of detachable column headings so arranged that the names of the stocks, as well as the ticker symbols, may appear in horizontal lines disposed centrally across the 25 heads of the respective columns. Preferably, all of the ticker symbols are arranged successively in the same horizontal line while the names appear alternately above and below the same. Plates bearing the designations for the respective columns are 30 arranged alternately in symmetrical relation to the horizontal center line of the space for headings and are secured by screws or similar fasteners placed at the inside corners of 35 the plates, in such a manner that the head of each fastener engages and acts as a retainer for two consecutive plates.

The invention will be more particularly 40 explained in connection with the accompanying drawings, in which

Figure 1 is a front elevation of a portion of a stock quotation board, with the invention shown in connection therewith.

Figure 2 is a detail sectional view taken 45 on the line 2-2 of Figure 1.

As shown in the drawings, the stock quotation board 3 is divided by vertical lines 4 into a series of columns in the usual manner. A series of plates are arranged at the top of 50 the board and have printed thereon the des-

ignations for the respective columns. Each of these plates includes a substantially square or rectangular shank 6 and a horizontally extended cross-head 5 integral therewith. These plates are adapted to be 55 arranged, as shown in Figure 1, with the shanks 6 arranged successively in a horizontal row, each shank being coextensive with the top of the column to which it pertains, while each head 5 extends equal distances 60 horizontally in each direction from the center line of the column. In the arrangement shown, the heads 5 of the plates are arranged alternately above and below the shanks so that each head extends horizontally for a distance equal to twice the width 65 of the column.

For detachably securing the plates to the board, a series of sockets 7 are threaded into or otherwise secured in the board 3 at the 70 corners of the respective shanks and a screw 8 or similar fastening device is secured in each socket so that the head of such fastener overlies and retains the contiguous corners of the adjoining shanks. By this means, the 75 plates are securely held but may easily be changed whenever it is desired to change the list of stocks to be quoted.

It will be seen that each shank is wide 80 enough to receive the ticker symbol of any stock which may be quoted in the column corresponding thereto and the head connected with the shank is long enough so that the common name of the stock or a readily recognized abbreviation thereof may be printed 85 horizontally on the head of the plate which is disposed horizontally across the top of the column.

While I have shown and described a practical form in which the invention may be embodied, it is to be understood that the invention includes all such modifications that may fall within the scope of the appended claims.

What I claim is:

1. A system of column headings comprising a plate for each column, each plate having a shank coextensive with the upper end of the column and bearing on its face a symbolic designation, a horizontally extended head integral with the shank and bearing horizontal- 95 100

ly on its face a more complete designation corresponding to the respective symbolic designation, said head and the designation thereon being centered with respect to the center line of the column, said shanks being in a horizontal row along the tops of the columns and said heads being arranged alternately above and below the shanks.

2. A system of column headings comprising a plate for each column, each plate having a shank coextensive with the upper end of the column and bearing on its face a symbolic designation, a horizontally extended head integral with the shank and bearing horizontally on its face a more complete designation corresponding to the respective symbolic designation, said head and the designation thereon being centered with respect to the center line of the column, said shanks being in a horizontal row along the tops of the columns and said heads being arranged alternately above and below the shanks, and fastening elements at the corners of the respective shanks, each fastening element having a retaining head overlying the contiguous corner portions of the adjoining shanks.

3. The combination with a board marked off in columns, of a plate at the upper end of each column and having a shank coextensive with said upper end for receiving a symbolic designation, a head integral with the shank and extending equal distances horizontally at each side of the shank for receiving a more complete designation, said shanks being in a horizontal row along the tops of the columns with the respective heads arranged alternately above and below the shanks, sockets secured in the board beneath adjoining corners of the shanks, and retaining elements engaging said sockets and having retaining heads, each of said retaining heads overlying contiguous corner portions of adjoining shanks.

In testimony whereof I have hereunto signed my name to this specification.

HERBERT R. WILSON.
